ROBERT FITTS, JR., OF FITCHBURG, MASSACHUSETTS, ASSIGNOR
TO W. HAYWOOD CHAIR COMPANY, OF THE SAME PLACE.

Letters Patent No. 87,404, dated March 2, 1869.

IMPROVEMENT IN MACHINE FOR BENDING WOOD.

The Schedule referred to in these Letters Patent and making part of the same.

To all whom it may concern:

Be it known that I, ROBERT FITTS, Jr., of Fitchburg, in the county of Worcester, and State of Massachusetts, have invented a new and improved Wood-Bending Machine; and I do hereby declare that the following is a full, clear, and exact description thereof, which will enable others skilled in the art to make and use the same, reference being had to the accompanying drawings, forming part of this specification, in which—

Figure 1, Sheet I, is a plan or top view of my improved machine, showing a strip of wood in place for bending.

Figure 2, Sheet II, is a front view of the same.

Figure 3, Sheet III, is a detail side view of the cam-gear, former-seat, cap, and centring-slide.

Figure 4, Sheet III, is a side or edge view of the former.

Figure 5, Sheet III, is a top view of the same, showing the bent strip and band in place.

Figure 6, Sheet III, is a detail end view, partly in section, of one of the cam-tables.

Figure 7, Sheet III, is a detail view of one of the adjustable stops.

Figure 8, Sheet III, is a detail sectional view of one of the extension-crank wrenches.

Figure 9, Sheet III, is a front end view of one of the extension-crank wrenches.

Figure 10, Sheet III, represents the two keys or keepers by which the bent wood is secured to the former.

Similar letters of reference indicate corresponding parts.

My invention has for its object to furnish an improved machine, designed especially for bending the frames of chair-seats, but which shall be equally adapted for bending wood for other purposes, and which shall be so constructed and arranged as to apply the pressure to the timber to be bent, gradually and progressively, until it is brought into the desired form; and

It consists in the construction and combination of the various parts as hereinafter more fully described.

A and B are two large gear-wheels, placed, the one above the other, upon the vertical standard or stationary shaft C, upon which they revolve independently of each other.

Into the teeth of each of the gear-wheels, A B, meshes the teeth of a small gear-wheel, D, attached to the shaft E, to which motion may be given by any convenient power.

To the upper part of the standard C is attached a stationary gear-wheel, F, made somewhat in the general form into which the timber is to be bent.

To each of the large gear-wheels A B is attached an arm, G, which is bent at right angles, and upon the upper ends of which are formed journals, upon which

work the hubs of the revolving cam-gear H, the teeth of which mesh into the teeth of the stationary gear F.

The cam-gear H are provided with an upwardly-projecting flange, h¹, which, as the cam-gear H move around the stationary gear F, press the timber to be bent gradually up against the former, bringing the said timber accurately into the desired form.

The cam-gear H h¹ should be made in such a shape as to press the timber close up against the former, from the middle point of said timber, where the pressure is first applied to the ends of the timber.

The forward ends of the flanges h¹ are made with an offset h², to receive the caps by which the ends of the timber are held while being bent, and with an adjustable screw-stop, h³, to support or press up the end of the timber, and hold it until secured by the keys or keepers.

I is the former, which is made of exactly the shape which it is desired the timber should have when bent. The former may be so formed that the timber, when bent, may be in a horizontal position. Or it may be formed upon a spiral, so that the ends of the bent timber may overlap each other as shown in fig. 5. The latter construction I prefer, as it allows the different parts of the machine to be made smaller than would otherwise be possible.

J is the former-seat, which is securely attached to the upper part of the standard C, and which is so formed as to hold the former, I, steady and firm while the timber is being bent upon it, and, at the same time, so formed as to serve as a table or flange to said former, for the lower side of the timber to rest upon during the operation.

K is a cap, which is hinged to a standard, L, in such a position that it may be turned down over the upper end of the standard C, upon the former I, beyond which it projects, so as to serve as a guard to keep the timber down to its place, while being pressed against the former I; the seat J and cap K thus forming a channel, into which the timber is pressed against the former I, by the cam-gear H.

The cap K, when lowered upon the former I, and former-seat J, is secured in place by the bolt M, which passes through a hole in the upper end of the standard C, and the rear end of which is pivoted to the lever N, by which it is operated, and the lower end of which is pivoted to the former-seat J, or to a collar placed upon the upper part of the standard C.

The lower end of the standard L is secured to the horizontal bar O, one end of which is attached to the standard C, and supports the upper part of said standard, and its other end is attached to and supported by the standard F.

Q is the centring-bar, by which the middle part of the timber to be bent is clamped to the former I, before being operated upon by the cam-gear H h¹.

The bar Q slides through a hole in the standard L, and through a hole in the guide-standard o^1 , attached to the bar O.

The rear end of the bar Q is provided with a projection or pin, to enter a groove in the side of the cam-lever R, which is pivoted to the support o^2 , attached to the bar O, as shown in fig. 3.

To each of the gear-wheels, A B, is attached a bent arm, S, in sockets in the upper and outer ends of which work the spindles T, of the tables, the movement of which is limited by the slotted stops V, adjustably secured to the lower end of the said spindles T, by a setscrew, and the slot of which receives a projection or pin, formed upon or attached to the under side of the arm S, as shown in fig. 2.

To the upper ends of the spindles T are attached horizontal bars W, the lower side edges of the forward parts of which enter dovetailed grooves formed upon the lower sides of the tables U, so that the said tables may be moved back and forth upon the said bars.

X are cam-levers, which are pivoted to standards attached to the rear ends of the bars W, and in the sides of which are formed curved grooves to receive the hooks u^1 formed upon the rear sides of the tables U, so that the said tables may be moved forward and back by the said cam-levers X.

The tables U are formed with a horizontal part, u^2 , upon which the timber to be bent is laid and adjusted, and with a vertical part, u^3 , against which the timber rests while being pressed forward against the former I.

Y is a band, or strap, which is interposed between the timber to be bent and the vertical parts u^3 of the tables U, to enable the said timber to be more conveniently centred, and, by being pressed closely against the outer side of the timber, while being bent, to prevent the said timber from splintering or slivering at the points of sharpest bend.

At the central point of the rear side of the strap Y, is formed a point, which enters a hole or groove in the centre of the forward end of the centring-bar Q, for convenience in centring the timber.

To the ends of the strap Y are attached the caps A', to receive the ends of the timber to be bent, where the said ends of the timber rest against plates a^1 , sliding in said caps A', and to the rear sides of which are swivelled the forward ends of the screws a^2 , which pass in through the ends of the caps A', and have cross-heads formed upon their outer ends, as shown in fig. 5.

To the ends of the tables U are swivelled sockets B', in which slides longitudinally the extension or telescopic shank of the crank-wrench C', which is so formed as to be drawn together and extended, somewhat in the manner of a telescope, as shown in fig. 8.

Upon the forward end of the wrench C' are formed two jaws, $c^1 c^2$, the one stationary and the other movable, which are held together in proper position to receive and hold the cross-head of the screw a^2 by the spring c^3 , so that the end-pressure upon the timber may be relaxed when necessary.

In using the machine, the tables U are moved back so as to be in line, or nearly in line with each other.

The strap Y and caps A' are then adjusted upon the timber, and the strap and timber are placed upon the tables U, centred, and clamped to the former I by the sliding bar Q.

The tables U are now moved forward by means of the cam-levers X, to keep the timber a little in advance of the pressure-points.

One of the gear-wheels, as B, is then revolved, pressing the timber into place against the former I, where its end is secured to said former by one of the keys or keepers D'.

This table is now swung back, and the other one advanced in the same manner, pressing down the other end of the timber upon the former, where its end is secured by the other key or keeper D'.

The cap K is then turned back, and the former I, with the timber and strap Y attached to it, removed and laid aside.

Another former is then placed upon the former-seat, and the operation repeated.

It should be observed that a different former and cam-gear must be used for each different style of bending, the other parts of the machine not requiring change.

Having thus described my invention, I claim as new, and desire to secure by Letters Patent—

1. The revolving cam-gear H h^1 , constructed substantially as herein shown and described, in combination with the stationary gear F, as and for the purpose set forth.

2. The former I, constructed substantially as herein shown and described, in combination with the former-seat J, stationary gear F, and revolving cam-gear H h^1 , substantially as herein shown and described, and for the purpose set forth.

3. The former-seat J, and former-cap K, constructed and operating substantially as herein shown and described, in connection with the stationary gear F and revolving cam-gear H h^1 , as and for the purpose set forth.

4. The adjustable and movable cam-tables U, constructed and operating substantially as herein shown and described, in combination with the revolving cam-gear H h^1 , stationary gear F, former-seat J, and former-cap K, substantially as herein shown and described, and for the purpose set forth.

5. The extension-crank wrench C', constructed substantially as herein shown and described, in combination with the cam-tables U, and caps A' $a^1 a^2$ of the strap Y, as and for the purpose set forth.

6. The sliding centring and clamping cam-bar Q R, in combination with the revolving cam-gear H h^1 , revolving tables U, stationary gear F, former-seat J, former I, and former-cap K, substantially as herein shown and described, and for the purpose set forth.
